METALLIC PARTITION

David L. Paulding, New York, N. Y., assignor to
 National Steel Partition Co., Inc., a corporation
 of New York

Application August 9, 1940, Serial No. 351,938

4 Claims. (Cl. 189—34)

This invention relates to improvements in metallic partitions.

One of the objects of this invention is to provide a metallic partition construction which, when erected, will possess great rigidity and durability and the parts of which will be rigidly and securely interlocked.

Another object of my invention is to produce a metallic partition of the type hereinabove specified which will be formed of panel units that may be readily erected or assembled and disassembled.

Another object of this invention is, in a metallic partition, to provide a panel unit with an edge member embodying a hollow channel-shaped upright element provided with a web portion extending parallel to the edge to which it is attached and at a right angle to the plane of the panel member and having a prong-receiving aperture, and may comprise either an independent channel-shaped edge-closing member or a channel-shaped glass-receiving portion of an edge molding member, but in either case the channel-shaped member or portion forms a column-like upright or supporting member and the web thereof is provided with one or more and preferably a series of spaced prong-receiving apertures, and these members are securely fastened together by one or a plurality of interlocking fastening members having prongs adapted to engage the metal at the edge of the apertures of opposite webs to lock the elements and the panels of which they form part securely together.

Still another object of my invention is to provide, upon each interlocking fastening member, means for connecting, at an angle to the interlocking prongs, another panel upright or for resiliently clipping thereto a pilaster.

Another object of my invention is to produce a panel unit formed from side plates having inturned corner flanges provided, at the terminal edges, with oppositely arranged and outwardly disposed groove-forming hooks and channel-shaped edge members having inturned flanges adapted to slide into opposite grooves over the edges of the flanges to lock the side plates together, and provide a hollow channel-shaped edging member for the panel.

Another object of my invention is to provide upright channel-shaped elements and interlocking fastening means therefor which will be capable of universal application in metallic partitions and may be applied to "one-way partitions," which comprise panels extending in a single 50

plane, "two-way partitions," in which the panels are L-shaped, "three-way partitions," in which one or more panel units abuts a main row intermediate the ends thereof.

Another object of my invention is to provide simple and rigid fastening members for securely fastening and spacing the web-portions of channel-shaped edge members to each other to form a rigid partition post or posts, all parts of which are readily accessible for easy erection.

Still another object of my invention is to provide a fastening member capable of ready and quick insertion between members having such upright channel-shaped portions and which will be engageable with opposite surfaces of the web portion of such uprights and will simultaneously engage the inner and outer surfaces of a pair of channel-shaped elements of a panel unit or the like.

Another object of my invention is to produce a panel-unit construction in which channel-shaped hollow upright members are provided with prong-receiving apertures and to utilize a fastening member having a spaced prong adapted to be inserted through such apertures in adjacently positioned edge members of adjacent panel-units and to be seated on the web metal adjacent to the edges of said apertures.

Still another object of my invention is to utilize square fastening members with spaced edges having prong portions for locking adjacent panel-units together and additional edge portions adapted to engage and lock a third panel or a pilaster member in place over the fastener.

Another object of my invention is to provide fastening members comprising four edged cross-plates having prongs on two opposite edges and adapted to space and lock the channel-shaped hollow edge members and the panel of which they form part in rigid relationship to each other.

Still another object of my invention is to provide fastening members of the type hereinabove specified with wedge portions adapted to force pilaster flanges apart and adjacent grooves to permit clipping of pilasters or the like to such edges.

Still another object of my invention is to utilize a panel construction which will require a minimum number of screws or other fastening devices.

Still another object of my invention is to provide, in an interengaging fastening connection between uprights and spaced prongs of a fastening member, such as hereinabove referred to,

means on the uprights for locking such prongs in engaging or seated position.

Still another object of my invention is to provide, within the channel-shaped members, struck-up straps to provide pockets registering with the lower part of said prongs and into which such prongs extend so as to prevent any spreading movement of the prongs, and thus to cause a more secure, firm and stable interlocking of the parts and holding such fastening members firmly though removably in position.

Still another object of my invention is to provide, on fastener prongs of the type specified, a struck-up interlocking bead and to provide in an upright in registration with said bead slots into which said beads will extend to provide a resilient fastening connection between such prongs and said uprights.

With these and other objects in view, the invention comprises the combination of members and arrangement of parts so combined as to contact and co-operate with each other in the performance of the functions and the accomplishment of the results herein contemplated, and comprises in one of its adaptations the species or preferred form illustrated in the accompanying drawings, in which:

Fig. 1 is a view in front elevation of a partition embodying my invention;

Fig. 2 is a section on the line 3—3 of Fig. 1, looking in the direction of the arrows;

Fig. 3 is a three-way partition showing the use of my invention in connection with a clip fastening, pilaster molding and a third panel extending at right angles to the fastening members;

Fig. 4 is a perspective view of clip employed in connection with my panel;

Fig. 5 is a fragmentary section showing a fastening member or clip having a slightly modified form of prongs and mounted to provide an interlocking engagement between the prongs and uprights;

Fig. 6 is a perspective section showing my invention applied to a three-way partition;

Fig. 7 is a section through a three-way partition showing the clip illustrated in Fig. 5, employed as a fastening member, a clipping element for pilaster and an anchoring element for a screw connection;

Fig. 8 is a section on the line 8—8 of Fig. 7, looking in the direction of the arrows.

Referring now to these drawings, I have, in Fig. 1, illustrated a fragmentary partition embodying three sections, two of which are composed of panel units 1, 1, and the third includes a door 2, and in accordance with the preferred form of my invention, each of the sections in a given form of partition 1 is composed of units of substantially similar and standard construction with, of course, the modifications necessary to produce wall sections, doors and doorways and the like, and all such sections or units are pre-formed and built at the plant, shipped to the site of use and then erected, and it is, of course, desirable that the sections may be erected in the shortest period of time possible with the least possible effort, provided that a rigid, strong and durable partition is produced.

In accordance with my invention, when a unit is intended to receive a plate or panel 4 of glass or other suitable material, each panel unit preferably comprises a molding member 3 (which may be either a stile or rail), having a conventional glass-receiving groove 3', this member is connected to its adjacent member by an interlocking-joint in which one of the members is provided

with marginal backwardly-bent and oppositely-disposed flanges which, with the adjacent surface portion, assumes a hook-shaped configuration and provides a V-shaped outwardly-disposed groove. Thus, in Fig. 3, the member 3 is provided, at its opposite edges with marginal flanges 3^a, 3^b, which are bent backwardly and provide at the outer surfaces grooves 3^b into which in-turned marginal flanges 5' of a channel-shaped edge member 5 are slidingly interlocked. The member 5 has its web portion 5^a extending transversely across or through the partition at substantially right angles to the plane of the panel 4 and a similar interlocking connection is made at the opposite and adjacent edges, the hook-shaped flanges being provided on either the two interlocked members. These channel-shaped edge members thus enclose the edges of the panels and at the upright edges of the panels, said members are utilized in the partition as rigid channel-shaped post-sections and when these upright members of adjacent units are suitably spaced and rigidly connected to each other and fastened a rigid frame or skeleton for a post will be provided that will require only the further connection and fastening over the panel edges of a pilaster member or other closure.

To enable such spacing, rigid connection and fastening, the web portion of such a channel-shaped edge member 5 at each upright edge of the panel is provided with apertures extending from the outside to the inside of the channel and these apertures in adjacent upright edge members are arranged in parallel registering pairs, and in the preferred form of my invention illustrated in Figs. 1 to 8, inclusive, I utilize these registering pairs of apertures in the upright members to enable interlocking of adjacent edge upright members and panels together.

By the use of my fastening element, which is more particularly illustrated in perspective in Fig. 4, I am enabled to space, interlock and rigidly fasten such adjacent upright members together and also to provide for the connection of other parts thereto. Said fastening member comprises a transversely-disposed body portion 6 having at opposite edges 6' depending interlocking prongs 7 each of which is preferably extended outwardly from the edge 6' a slight distance substantially equal to the thickness of the metal being used so as to provide between the inner surface of the prong 7 and the edge 6' a tight seat for the reception of the metal of the web adjacent to the bottom of said apertures, and the bottom edges of these prongs 7 are provided with outwardly curved edges or lips 7' so as to facilitate the engagement of the same with the web metal at the edges of the opposite apertures and to enable the pulling-in and fastening together of such members. The interconnection and fastening of such fastening members and their prongs with a section of metal at the edges of the apertures of said web members provides for a spacing, alignment and secure fastening together of the panel units. In the said preferred embodiment of my invention, the aforesaid tight seat on the fastening member is formed by providing each of the edges 6' at opposite sides of the prongs 7 with abutment portions 8 extending parallel to but slightly spaced inwardly from the inner surface of the prong. These edge portions 8 are adapted to abut with and engage the other surface of the web portion 5^a of the member 5 at opposite sides of the aperture while the inner surface of

the prong 7 is in engagement with the inner surface thereof. In this way, when a fastener member is seated in registering apertures in the edge members 5, the web metal of said edge member will be pressed outwardly away from the panel edges by the prong and inwardly toward the panel edge by the edges 8 so as not only to produce a rigid and strong fastening connection between the said member 6 and the web metal of the hollow members 5, but to provide a reinforcement for such members and a secure and rigid interlocking connection therefor and furthermore, will produce a skeleton frame for the provision in the partition of a rigid post or posts.

In accordance with the preferred embodiment of my invention, the transversely-disposed body portion of my fastening member 6 is preferably of square configuration so as to provide two additional edges intermediate and adjacent to the pronged edges 6^a hereinabove referred to and each of these intermediate edges 6^a is provided with means for fastening to the member 6 another partition section or a pilaster or pilasters 9. The pilasters 9 are resiliently fastened and for this purpose I provide each edge 6^a at the corners thereof, with projections 10 having wedge or spreading surfaces 10^a adapted to engage terminal inwardly-extending flanges 9^a of the pilaster 9 during an inward applying movement of said pilaster to spread such flanges outwardly and then to interlock with grooves 11 so as to resiliently engage the pilaster and hold the same in place for the purpose of closing the space between panel edges and finishing the appearance of the partition and/or producing a post therein. While in some cases a pilaster 9 will be applied at opposite sides of the member 6 so as to produce a finished post in a two-way single partition, it is in many cases necessary to have a three-way partition such as illustrated in Fig. 4 and for the purpose of providing a fastening connection for a third leg of a partition, I also provide at the edge 6^a of the fastening member 6 separate tongues 12 preferably projecting upwardly, and each tongue 12 is provided with a fastening notch 12^a. In said preferred embodiment the notches 12^a are utilized to receive and abut the head 13^a of a bolt 13 which is adapted to project through one of the standardized apertures 5^b in an upright member 5 of the third partition leg, as more particularly shown in Fig. 7.

In the form shown in Figs. 3 and 7, an elongated bridge member 13^a is preferably positioned at the inner side of the aperture and provided with a screw-threaded opening through which the bolt 13 extends. Obviously, when the head of the bolt abuts the edges of the kerf or notch 12^a and the bridge member 13^a abuts the opposite edges of the aperture 5^b, the bolt may be tightened up as rigidly as desired and the panel 1 of the third partition leg will be securely mounted and fastened in place.

In Fig. 7 I have shown an extremely simple form of interlocked panel construction comprising oppositely disposed side plates 1^a, 1^a each having corner bends 1^d and inturned flanges 1^c, the marginal edges 1^d of which are bent backwardly to provide hook-shaped portions which form oppositely-disposed grooves 1^e. These grooves receive and interlock with flanges 5^b of the hollow edge member 5 in the same way as hereinabove described in relation to the interlocking connection between said member 5 and

the glass-receiving member 3 in Fig. 3 and the glass-receiving member 3^a of Fig. 2. In the last-mentioned construction, the backwardly-turned flanges 1^d are similarly formed on the side panel edges while in Fig. 3 the hook-shaped flanges are formed on the molding member 3, but in other respects the interlocking connections are similar.

The panel of Fig. 7 may be entirely hollow and plates 1^a may be suitably fastened to an edge reinforcing member 14 or, if desired, the panel may contain a filler such as indicated at 15 in Fig. 7.

In the preferred form of my invention, means is preferably provided to further lock the prongs 7 to the upright members and for this purpose upright channel members such as shown in Figs. 3, 4 and 6 to 8 are provided as more particularly shown in Fig. 5 with pairs of slots 7^b into which the curved lip portions 7^c extend, and, although the frictional locking shown in Fig. 8 operates to effectually hold the parts together, I also preferably provide the prongs 7 with a more pronounced struck-up locking bead 7^a such as shown in Fig. 5. In either event, an additional special locking connection between the prong and upright member is provided which prevents any tendency of the fastening member 6 to loosen up.

It will be seen, therefore, that I have provided a hollow channel-shaped member having its web portion extending parallel with the edge of the unit and at right angles to the plane of the panel and that such a member may either comprise a special separate member used for that purpose as shown in Figs. 1 to 8.

Having described my invention, I claim:

1. In a metallic partition, the combination of a plurality of units, each unit provided with a channel-shaped upright edge-member having its channel-web portion extending in a vertical plane transversely of the partition and in parallel relationship with the edge of the unit, said upright edge-members being arranged in adjacently-positioned pairs having their channel web-members spaced from each other and provided with pairs of prong-insertion registering apertures, a plurality of independent spacing clips, each having a transversely-disposed body-portion comprising a spacing plate provided at opposite edges with outwardly and downwardly-projecting pronged portions, said plate together with the outwardly-projecting parts of the pronged portions being of greater width than the distance between the vertical planes of said web-portions and said prong portions being extensible through said pairs of registering apertures therein to engage inside surfaces of the web-portions within the channels of said upright members, said spacing plates also having at opposite sides of and adjacent to each pronged portion, additional web-engaging portions simultaneously engageable with outside surfaces of said web-portions, whereby upon insertion of the clip between said apertured webs and movement thereof into final position each of said opposite edges of the spacing plate will have tight oppositely-engaging triple-contact interlocking connections with adjacent portions of opposite surfaces of the web-portion of one of said channel-shaped upright members and flexing of such web-portion adjacent to the connections is prevented, additional partition parts, and means for connecting to said uprights said additional partition parts to produce a closed post.

2. In a metallic partition, the combination of a plurality of units, each unit provided with a channel-shaped upright edge-member having its channel-web portion extending in a vertical plane transversely of the partition and in parallel relationship with the edge of the unit, said upright edge-members being arranged in adjacently-positioned pairs having their channel web-members spaced from each other and provided with pairs of prong-insertion registering apertures, a plurality of independent spacing clips, each having a transversely-disposed body-portion comprising a spacing plate provided at opposite edges with outwardly and downwardly-projecting pronged portions, said plate together with the outwardly-projecting parts of the pronged portions being of greater width than the distance between the vertical planes of said web-portions and said prong portions being extensible through said pairs of registering apertures therein to engage 20 inside surfaces of the web-portions within the channels of said upright members, said spacing plates also having at opposite sides of and adjacent to each pronged portion, additional web-engaging portions simultaneously engageable with outside surfaces of said web-portions, whereby upon insertion of the clip between said apertured webs and movement thereof into final position each of said opposite edges of the spacing plate will have tight oppositely-engaging 30 triple-contact interlocking connections with adjacent portions of opposite surfaces of the web-portion of one of said channel-shaped upright members and flexing of such web-portions adjacent to the connections is prevented, and an additional locking connection between said webs and pronged portions disposed adjacent to the said pairs of prong-insertion registering apertures to prevent loosening of said pronged portions, and means at another edge of said body for fastening said additional partition parts thereto to enclose said fastening member and produce a closed post.

3. In a metallic partition, the combination of a plurality of units, each unit provided with a channel-shaped upright edge-member having its channel-web portion extending in a vertical plane transversely of the partition and in parallel relationship with the edge of the unit, said upright edge-members being arranged in adjacently-positioned pairs having their channel web-members spaced from each other and provided with pairs of prong-insertion registering apertures, additional partition parts, a plurality of independent spacing clips, each having a transverse-

ly-disposed body-portion comprising a spacing plate provided at opposite edges with outwardly and downwardly-projecting pronged portions, said plate together with the outwardly-projecting parts of the pronged portions being of greater width than the distance between the vertical planes of said web-portions and said prong portions being extensible through said pairs of registering apertures therein to engage inside surfaces of the web-portions within the channels of said upright members, said spacing plates also having at opposite sides of and adjacent to each pronged portion, additional web-engaging portions simultaneously engageable with outside surfaces of said web-portions, whereby upon insertion of the clip between said apertured webs and movement thereof into final position each of said opposite edges of the spacing plate will have tight oppositely-engaging triple-contact interlocking connections with adjacent portions of opposite surfaces of the web-portion of one of said channel-shaped upright members and flexing of such web-portions adjacent to the connections is prevented, and an additional locking connection between said webs and pronged portions disposed adjacent to the said pairs of prong-insertion registering apertures to prevent loosening of said pronged portions, and means at another edge of said body for fastening said additional partition parts thereto to enclose said fastening member and produce a closed post.

4. In a metallic partition, the combination of a plurality of units, each unit comprising side members and including a channel-shaped upright edge member having its channel-web portion extending transversely of the partition and in parallel relationship with the edge of the unit, said side and edge members being connected by an interlocking joint embodying a pair of oppositely-arranged hook-shaped marginal portions on one part to provide outwardly-disposed grooves and a pair of inwardly-disposed marginal flanges on the other part, and said upright edge-members being arranged in adjacently-positioned pairs having their channel web-members spaced from each other and provided with pairs of registering apertures, fastening members of greater width than the distance between the web-portions of such uprights and extending within said registering apertures to engage the web portion at the inside of said apertures to provide an open skeleton post, and means on said bridging member for connecting to said uprights other partition parts.
